UNITED STATES PATENT OFFICE

99,878

DESIGN FOR AN AUTOMOBILE HOOD RIDGE ORNAMENT

Paul Marienthal, Detroit, Mich.

Application June 17, 1935, Serial No. 57,296

Term of patent 3½ years

To all whom it may concern:

Be it known that I, Paul Marienthal, a citizen of the United States and a resident of Detroit, Michigan, have invented a new, original, and ornamental Design for an Automobile Hood Ridge Ornament, of which the following is a specification, reference being had therein to the accompanying drawing.

Fig. 1 is a side elevation view of an automobile hood ridge ornament showing my new design;

Figs. 2 and 3 are enlarged sectional views as on the lines 2—2 and 3—3 of Fig. 1.

What I claim is:

The ornamental design for an automobile hood ridge ornament, substantially as shown.

In testimony whereof I affix my signature.

PAUL MARIENTHAL.
